(57) **CLAIM**

The ornamental design for a hexagonal game piece holder with card slots, as shown and described.

DESCRIPTION

FIG. 1 is an isometric view of a hexagonal game piece holder with card slots.

FIG. 2 is a top view of a hexagonal game piece holder with card slots.

FIG. 3 is a bottom view of a hexagonal game piece holder with card slots.

FIG. 4 is a right-side view of a hexagonal game piece holder with card slots. The left-side view, which is omitted from the figures, is a mirror image of the right-side view; and, FIG. 5 is a side view of the hexagonal game piece holder with card slots that is rotated 30 degrees with respect to the view in FIG. 4.

In the drawings, the broken lines depict portions of the hexagonal game piece holder with card slots that form no part of the claimed design.

The hexagonal game piece holder with card slots may be used on a tabletop or other surface to hold game cards, playing cards, and/or similar objects.
